UNITED STATES PATENT OFFICE

1,953,993

ABSORPTION REFRIGERATION

Donald G. Smellie, Canton, Ohio, assignor to The
Hoover Company, North Canton, Ohio, a cor-
poration of Ohio

Application October 22, 1930, Serial No. 490,497

22 Claims. (Cl. 62—119.5)

This invention relates to refrigerating apparatus and more particularly to systems of the type in which an inert gas is employed as a pressure equalizing medium so that the total pressure therein is substantially the same throughout the system, but the partial pressure of the refrigerant differs in different parts so as to enable the refrigerant to evaporate and produce a cooling effect at a lower temperature than that at which it is changed to a more dense phase.

As disclosed in the United States patent to Geppert 662,690, a continuously acting refrigerating system may be constructed and operated without the use of an expansion valve or the like provided an inert gas is employed as a pressure equalizing medium in certain parts of the system. This principle, which is now well known, is employed in obtaining a cooling effect in accordance with the present invention although the manner in which it is used, and the process as a whole differs widely from that suggested by Geppert.

This application contains subject matter in common with my prior co-pending application, Serial No. 169,765, filed February 21, 1927, for "Refrigeration", now Patent No. 1,818,587, patented August 11, 1931, so that it relates back thereto insofar as the common subject matter is concerned.

An object of the present invention is to provide a continuous absorption refrigerating system employing an inert gas and operating upon a new principle in which a refrigerant is conveyed into an evaporator by a strong solution from which it evaporates into the inert gas to produce the cooling effect after which the solution is then conveyed to a boiler where it is further weakened by the application of heat, so that it may subsequently absorb the refrigerant expelled in the evaporator out of the inert gas. The refrigerant expelled in the boiler is then conveyed to a second absorber which contains no inert gas, where it is then absorbed and returned by the strong solution to the evaporator. In other words, a single absorption liquid is circulated through a system of vessels consisting essentially of an evaporator, a boiler and two absorbers which are inter-connected. The thermodynamic environment in the vessels is varied by circulating an inert gas through the evaporator and one absorber and by the application of heat to the boiler, and removal of heat from the absorbers so that refrigeration is effected in the evaporator.

A further object is to provide a continuous absorption refrigerating system adapted to operate

without moving parts and in which all of the parts are hermetically sealed together.

Another object of the invention is to provide a continuous absorption refrigerating system in which the pressure at which the unit operates may be relatively low, for example not more than one or two atmospheres, although the invention is not limited to operation at such pressure.

Other objects and advantages of the invention will be apparent from the following description taken in connection with the accompanying drawings in which Fig. 1 is a more or less dia- 60 grammatic showing of a system of inter-connect- 65 ed vessels, illustrating a system adapted to carry out certain of the principles of the invention.

Fig. 2 is a diagrammatic showing of another embodiment of the invention in which no moving parts are employed.

Fig. 3 illustrates an apparatus in which various mechanical expedients, now well known in the art, have been added to improve the operation of systems such as those shown in Figs. 1 and 2.

Fig. 4 is an illustration of a different form of practical working apparatus somewhat similar to that of Fig. 3, but in which the parts are some- 75 what differently arranged.

Fig. 1 illustrates the basic principle involved in this invention. As there shown the apparatus consists of an evaporator E, a boiler or generator 80 in the form of a coil as shown at B, a gas separating chamber S, two absorbers designated A₁ and A₂, two heat exchangers, one for the solution designated by the reference character 10 and one for the gas designated by the numeral 11. A fan 85 or blower for circulating the gases in heat ex- 90 changer 11 is shown as 12. These various de- 95 vices may be of any suitable well-known con- struction and are connected together by pipes as shown.

The evaporator E may be provided with a coil as shown at 13 for conducting heat from a device to be cooled to the evaporator by circulating brine or the like therethrough. It is, of course, to be understood that the invention is not limited to this indirect manner of cooling, but the evaporator may be placed in a refrigerator cabin- 100 net or the like so as to cool it directly.

The boiler B is in the form of a small coil of pipe which may be heated by an electric car- 105 tridge heater such as is shown at 14, or by a gas flame or other suitable source of heat. This coil not only acts to expel gas from the solution therein but also acts as a pump. For a full disclosure of this device reference may be had to 110

- Altenkirch Patent 1,728,742. Both absorber A₁ and A₂ may be provided with coils such as are shown at 15 or 16 for conveying heat away therefrom by circulating cooling water through them.
- 5 Obviously other forms of water cooled absorbers may be used such as those in which the water is circulated through a jacket around the body of the absorber or if desired the absorbers may be air-cooled in which case suitable heat radiating fins should be placed upon them.
- 10 As shown, the separator may be an ordinary vessel. In addition to the heat supplied to the boiler B, heat may also be supplied to separator S by a gas flame or the like if desired.
- 15 The heat exchangers may be of any conventional type. As shown they are made up of two concentrically disposed pipes so that the heat may readily be conveyed from the fluid in one to the fluid in the other.
- 20 The fan 12 may be of any suitable construction and driven by an electric motor or the like.
- The apparatus operates as follows:—
- Assuming a quantity of aqua-ammonia of a concentration, say of between 20 and 40% has 25 been placed in the apparatus through suitable valves not shown until it has filled the heat exchanger and the lower half of the evaporator E, absorbers A₁ and A₂, boiler B and separator S and that air is in the remainder of the machine 30 at approximately atmospheric pressure. Upon heat being supplied to the boiler B, and upon the fan 12 being started gases will circulate from the evaporator through the outer conduit of the heat exchanger 11 into the absorber A₁ and back to 35 the evaporator through the fan 12 and inner conduit of the heat exchanger 11. Circulation of the absorption solution will also begin because of the formation of bubbles in the boiler B. The solution circulation is as follows:—
- 40 From the evaporator E through the conduit 18, boiler B, gas separating chamber S, conduit 19, absorber A₁, conduit 20, outer conduit of heat exchanger 10, conduit 22, absorber A₂ and conduit 23 back into the evaporator.
- 45 As the solution is circulated by the novel action of the boiler referred to, ammonia is expelled therefrom and as this ammonia gas separates from the liquid in the separating chamber S it passes through the conduit 24 into the absorber 50 A₂. The solution thus weakened is conveyed from the separator through the conduit 19 into the absorber A₁ where it comes in contact with the inert gas such as air (or hydrogen) which is laden with ammonia gas from the evaporator and 55 at the temperature prevailing in the absorber A₁ the weak solution picks up or absorbs the ammonia out of the inert gas. It is of course, obvious that if refrigeration is to be produced, evaporation of refrigerant in the evaporator E must take place at a lower temperature than that at which it is absorbed in the absorber A₁. It is therefore necessary that the solution conveyed to the absorber be considerably weaker than that in the evaporator since the total pressure in the 60 two is the same. Thus the function of the boiler B is to weaken the solution to enable it to pick up ammonia in the absorber A₁. The solution strengthened in A₁ is conveyed through the conduit 20, outer conduit of the heat exchanger 10 and conduit 22 into the absorber A₂. Now in the absorber A₂ as well as in the separator S, conduit 24 and boiler B, there is no inert gas. Thus in the evaporator and in the absorber A₁ the ammonia partial pressure is less than the 65 total pressure in the machine by the amount of 70

the inert gas partial pressure therein, while the ammonia vapor pressure in the boiler and absorber A₂ is approximately equal to the total pressure in the machine. Under these conditions the solution entering absorber A₂, may pick up an additional amount of ammonia gas this being conveyed from the boiler through the conduit 24. This solution, which is the strongest of any in the apparatus, is then conveyed to the evaporator through the conduit 23 and evaporation again takes place into the inert gas as recited above.

It will thus be apparent that the solution, in passing through a complete cycle is subjected to a process in which: (1) The refrigerant, as ammonia is evaporated into the inert gas as air to produce a cooling effect in the evaporator where the partial pressure of the refrigerant is low.

(2) Refrigerant is evaporated in the boiler by the application of heat without inert gas being present so that the partial pressure of the refrigerant is high.

(3) Refrigerant is absorbed from the inert gas in the absorber A₁ where the partial pressure of the refrigerant is low and

(4) Refrigerant is absorbed in the absorber A₂ where the partial pressure of the refrigerant is high.

It will also be seen that there is only one solution cycle in the apparatus and that the refrigerant evaporates in the evaporator from the solution rather than from a nearly pure liquid state as contemplated in most absorption refrigerating apparatuses. The absorber A₂ is in some respects similar to the condenser of the conventional inert gas absorption machine, such as shown by Geppert but since it is not necessary to condense the refrigerant but only to absorb it into a solution the apparatus may operate under a total pressure lower than that suggested by Geppert.

The apparatus of Fig. 1 is only intended to illustrate the principle involved and does not employ efficient means for bringing the liquid and gases into intimate contact to effect proper evaporation and absorption although such expedients are contemplated as will be evident after consideration of Figs. 3 and 4 hereinafter described.

Referring now to Fig. 2, the diagram illustrates a unit like that of Fig. 1 except for the means employed for circulating the fluids. The evaporator E, absorber A, boiler B and separator S may be of the same construction as described in connection with the arrangement of Fig. 1 although their relative positions are not the same.

A jet or nozzle 25, in cooperation with a suitable venturi 26, causes the circulation of the inert gas through the pipes 27 connecting the evaporator E and absorber A. The jet is supplied with a portion of the refrigerant gas driven out of the solution in the boiler B and separator S.

The separator being located below the absorber gravity cannot be used, in causing the solution to flow from it to the absorber A₁, but the pressure created by expelling the refrigerant from the solution in the boiler B and separator S forces the solution up into the absorber A₁.

The refrigerant gas, except for the small part which feeds the jet is conveyed by the pipe 28 to a point below the absorber A₂ where it mixes with solution coming from the absorber A₁ through the pipe 29. The mixture of refrigerant gas and solution then rises through the absorber A₂ where the gas is absorbed in the solution, the

fluid then flowing into the evaporator, this column of fluid also being under the influence of the pressure generated in the separator S and boiler B. The absorber A₂ being in the form of a small coil, it also functions as a gas lift pump.

In the diagram of Fig. 2 no heat exchangers are shown but their use is obvious in view of the showing in Fig. 1.

In Fig. 3 a machine is illustrated in which well known types of baffled evaporators and absorbers are employed and in which various other devices such as a rectifier, a receiver, and a vent pipe for conveying gases away from the absorber A₂ are employed for improving the operation of apparatus like that shown in Figures 1 and 2. In Fig. 3 the parts corresponding to those of Fig. 1 are similarly designated, these being the evaporator E, the boiler B, separator S and absorbers A₁ and A₂.

As shown in Fig. 3 the evaporator E and absorber A₁ consist of vertically disposed cylindrical vessels provided on their inside with a series of plates or baffles. These plates may be made of sheet metal disks with segments cut away and may be slightly cupped if desired. In assembling, the cut away portions are staggered to cause fluids flowing thru the vessels to travel over a tortuous path. The absorber A₂ of this figure is shown as made up of two concentric coiled pipes, the outer pipe serving merely as a jacket thru which water may circulate to cool the fluids in the inner pipe. The boiler B is of a known construction and consists of a cylindrical drum 30 having a tube 31 extending horizontally therethrough for receiving an electric cartridge heater 32. The pipe 33 is of small diameter and cooperates with the main drum 30 of the boiler to obtain a pumping action similar to that of the boiler B in Fig. 1, the liquid being carried upward therein by the lifting action of gas or vapor which form therein. The separator is an ordinary vessel provided with two outlets as shown, one at the bottom and one near the upper portion thereof. It may be provided with a heater if desired.

In addition to the elements mentioned above the system of Fig. 3 is also provided with a vertically extending cylinder 35 which acts as a reservoir and a rectifier, the upper portion being provided with a series of baffles 36 for this purpose. The refrigerant vapor enters the cylinder 35 below the baffle plates through the conduit 37 and as it passes upwardly over them to the conduit 38, the water vapor entrained with it is condensed. The water collects in the bottom of the cylinder 35 and is conveyed back into the drum 30 of the boiler thru the conduit 39. The lower end of the cylinder 35 may be provided with a tube 40 held in place by a plate 41 opposite the conduit 39 to prevent surges, occasioned by sudden expulsion of vapor from the solution in the boiler, from adversely affecting the operation of the system.

The upper portion of the conduit 38 which conveys vapor away from the cylinder 35 may be inclined slightly from the horizontal as shown and provided with radiating fins 43 to provide additional rectification. This pipe then extends downwardly and is joined to one leg of a U-shaped pipe 44 which conveys absorption liquid out of the absorber A₁ into the absorber A₂, this union being a suitable distance below the absorbers. The left hand leg of the U-shaped pipe 44 being of small diameter, a pumping or lifting action is obtained by mixing gas from the conduit 38 with

the liquid in the conduit 44 for conveying the absorption liquid from the absorber A₁ to the absorber A₂ at a higher level. This action is similar to that which takes place in the riser pipe 33 except that here the gas is fed into the pipe from a point without. As the refrigerant gas and absorption liquid rise through the conduit 44 they are of course in intimate contact and some absorption takes place. As the solution passes thru the coils of absorber A₂ more refrigerant is absorbed and carried away with the solution thru the conduit 45. Should any of the refrigerant gas not be absorbed or should any of the inert gas become entrained in the absorption liquid and carried into the absorber A₂, as sometimes happens in devices of this nature, it will collect in the small vessel 46 shown at the left hand side of the absorber A₂ and be conveyed thru the conduit 47 back into the absorber A₁ after passing thru a device called a swallower 48. This swallower functions merely to maintain a liquid seal for preventing the passing of gases from the absorber A₁ to the chamber 46. In making up the swallower, a pipe 49 which may be concentrically disposed with respect to the right hand leg of the U-pipe 44, as shown, is connected to the lower end of the absorber A₁ and has an auxiliary conduit 15 arranged along side thereof which is connected to it at the bottom and connected to the lower end of the absorber A₁ at the top. These two pipes being filled with liquid, as absorption solution, when gas from the vessel 46 is fed into the auxiliary pipe 15 thru the pipe 47, the liquid in the swallower rises thru the conduit 50 and flows downwardly thru the conduit 49 while at the same time maintaining an adequate seal and preventing surges or fluctuations, caused by changes in pressure which might otherwise occur.

Absorption liquid conveyed by the pipe 45 out of the absorber A₂ is fed into the lower end of a conventional heat exchanger 52 and conveyed thru the outer conduit thereof and the pipe 53 to the upper end of the evaporator. For conveying the absorption liquid from the evaporator back to the boiler, the conduit 54 connects the evaporator to the inner coil of heat exchanger 55 which is in turn connected to the lower end of the reservoir cylinder 35. The pipe 56 conveys absorption liquid from the separator S thru the outer conduit of the heat exchanger 55 to the absorber A₁ thru the conduit 57. To prevent an accumulation of an excess of absorption liquid in the absorber A₁ an overflow pipe 58 connects it to the conduit 54 so that the excess may drain back into the boiler. Like the construction shown in Fig. 1 means is provided for circulating an inert gas such as air or hydrogen between the evaporator and absorber A₁. For this purpose conduits 60 and 61 are disposed between these vessels, portions of the two being in heat exchange relation as shown at 62. In place of the fan 12 of Fig. 1, a jet is used for obtaining circulation of the gases. A portion of the conduit 61 is restricted as shown at 63 to provide a suitable venturi thru which the gases are forced by a nozzle 64 fed by refrigerant gases from the separator by the conduit 65. The portion of the refrigerant gas fed to the nozzle produces no useful cooling effect but since this is only a small portion of that expelled from the solution in the boiler, this loss is not of great consequence.

This apparatus is charged and operated as follows:—

A quantity of suitable refrigerant such as ammonia together with a solvent such as water is placed in the apparatus thru suitable valves, not shown, until it has filled the lower portion of the apparatus and has risen to a level slightly below the point where the conduit 37 is connected to the reservoir 35. There being some air collected in the upper part of the machine, it will probably not be necessary to add any more but should it be necessary, air under pressure may be fed into the evaporator or absorber A₁ from a suitable source to raise the pressure above atmospheric before application of heat to the boiler. Obviously hydrogen or other inert gas may be used instead of air. If desired, the entire system may be swept out with ammonia gas in the usual manner before the inert gas is supplied. After the charging valves are closed, heat may be supplied to the boiler and cooling water run to the absorber A₂. In this connection it should also be observed that either or both absorbers may be air or water cooled. In the construction shown the absorber A₁ is air cooled and the absorber A₂ is water cooled.

As heat is supplied to the drum 30 of the boiler the solution rises thru the conduit 33 because of the formation of gas bubbles therein and is conveyed to the separator S where the refrigerant gas leaves the solution thru the conduit 37. The weakened solution passes downwardly thru the conduit 56, outer coil of heat exchanger 55, conduit 57 into the upper end of absorber A₁. After trickling down over the plates in the absorber A₁ the solution which has been enriched in this absorber by absorbing refrigerant from the inert gas therein passes thru the conduit 54 and is lifted into the absorber A₂ after mixing with refrigerant gas conveyed thru the conduit 38 into the conduit 44. More refrigerant being absorbed in the absorber A₂, this enriched solution passes thru the conduit 45, outer pipe of heat exchanger 52, pipe 53 into the upper end of the evaporator. As it trickles down over the baffle plate in the evaporator, the refrigerant evaporates out of this rich solution into the inert gas. The solution thus weakened passes downwardly thru the inner pipe of heat exchanger 52, conduit 54, inner pipe of heat exchanger 55, lower portion of reservoir 35 and conduit 39 back to the boiler thus completing its cycle. The refrigerant expelled in the boiler after passing thru the conduit 37 rises thru the rectifier plates 36 in the upper end of the reservoir cylinder 35 and passes thru the conduits 38 and 44 into the absorber A₂.

The refrigerant gas which has evaporated from the solution in the evaporator to produce a cooling effect is carried by the inert gas thru the conduit 61 into the absorber A₂ where it is absorbed again as explained above, the weakened inert gas being returned to the evaporator thru the conduit 60.

It will thus be seen that this system operates fundamentally the same as that illustrated in Fig. 1. Since, however, the absorber A₂ is located above the absorber A₁ it is necessary that the solution be lifted twice, once in the conduit 33 and once in the conduit 44. The ratio of the lifting height to the height of the liquid in the reservoir 35 and the point at which the conduit 38 is connected to the conduit 44 are thus important factors in a proper design of this apparatus. These and other factors encountered in the use of gas lift pumps are now well known to those skilled in the art being discussed among others 75 in a publication entitled, "Über Messungen an

kleinen Mammupumpen (Measurements of Small Air-Lift Pumps) by Dr. K. Nesselmann, Vol. IV, No. 1, 1927, of Wissenschaftliche Veröffentlichungen aus dem Siemens-Konzern," this being a publication of the Siemens-Schuckertwerke, Berlin-Siemensstadt, Germany. It will be noted that in the unit shown in Figure 3, like the one shown in Figure 2, the pressure in the gas separating chamber S is higher than that in the absorber A₂ and that this excess of pressure is utilized to force solution into the absorber A₂, since it cannot be conveyed by gravity from the lower end of absorber A₁ into the absorber A₂ at a higher level. Figure 4 illustrates an apparatus in which the solution may flow by gravity from the separator S into the absorber A₁, from there into the absorber A₂ and from there into the evaporator E without the interposition of any gas lift pump being necessary. Because of its similarity to that of Figure 3, a full description 80 of this figure will not be necessary except insofar as the operation of the absorber A₂ is concerned and the manner in which the fluids are circulated.

The absorber A₂ consists merely of a pipe 70 100 with an outlet pipe 71 extending through the end closure 72 at the lower end and up to a point slightly below the lower end of the absorber A₂.

This unit being charged and heat applied to 105 the boiler, the path of travel of the solution may be traced as follows:

Starting with the boiler B, the solution is lifted by the formation of refrigerant gas bubbles in the pipe 73 into the separator S from which it 110 flows downwardly through the conduit 74, outer pipe of heat exchanger 75, upwardly through pipe 76 into the top of the absorber A₁, through the absorber A₁ and U pipe 77 into the lower end of absorber A₂ where as it rises, it mixes with 115 and absorbs the gas entering the absorber A₂ from the separator S through the conduit 78. The solution then passes downwardly through the conduit 71 into the outer pipe of heat exchanger 79 through the heat exchanger and pipe 120 80 into the top of evaporator E and back to the boiler through the conduit 81, inner pipe of heat exchanger 79, conduit 82, inner pipe of heat exchanger 75 and conduit 83.

An inert gas circuit is provided between the 125 evaporator and the absorber A₁ by means of the pipes 84 and 85, portions of which are in heat exchange relation, as shown at 86. A jet 87, similar to that described in connection with the structure of Fig. 3 is supplied with a portion of 130 the refrigerant gas expelled in the separator 88 through the conduit 88.

The upper end of absorber A₂ takes the place of the small vessel 46 of Fig. 3 and provides means for the collection of any gases which have not been absorbed in the absorber A₂. These gases 135 are carried away through the conduit 89 into a swallower 90 which is of a slightly different construction than that of Fig. 3. As shown it consists of two pipes arranged concentrically with 140 a portion of the U-pipe 77 and secured to the lower end of the absorber A₁. The upper and lower edge of the inner pipe 91 of this swallower are provided with openings or holes such as shown at 92 so that the liquid which maintains a seal 145 in the swallower may flow upwardly between the inner and outer pipes upon gas entering the pipe 89 and then flow downwardly between the inner pipe of the swallower and the portion of the conduit 77 which is inside thereof. A perforated 150

cap 93 may be secured to the upper end of the inner pipe 91 of the swallower if desired.

While various embodiments of the invention have been shown and described, it is obvious that the invention is not limited to the particular construction shown and that various changes can be made without departing from the spirit of the invention or the scope of the annexed claims.

10 I claim:—

1. In an absorption refrigerating system the combination with an evaporator and an absorber of means for circulating an inert gas between and thru said evaporator and said absorber and for maintaining substantially the same pressure therein, means for circulating a solution consisting of a refrigerant and a solvent therefor between and thru said evaporator and said absorber, and means for removing refrigerant from the solution as it passes from the evaporator to the absorber and for replacing it in the solution as it passes from the absorber to the evaporator, to thereby cause the average concentration of the solution in the absorber to be maintained lower than the average concentration of the solution in the evaporator and permit the refrigerant to evaporate from the solution in the evaporator into the inert gas therein to produce a cooling effect and be absorbed out of the inert gas by the solution in the absorber at a higher temperature than that prevailing in the evaporator.

2. In an absorption refrigerating system an evaporator, an absorber, means connecting the evaporator and absorber for holding inert gas therein, means for conveying a solution of refrigerant thru the evaporator and absorber, means for causing the refrigerant to evaporate in the evaporator into the inert gas and means for causing the solution to absorb the refrigerant out of the inert gas in the absorber and return it to the evaporator.

3. In an absorption refrigerating system, the combination with an evaporator and an absorber of means for circulating an absorption solution between them, and means for removing refrigerant from the solution as it passes from the evaporator to the absorber and for replacing the refrigerant in the solution as it passes from the absorber to the evaporator.

50 4. In an absorption refrigerating system, the combination with an absorber of means for circulating an absorption solution therethrough and means for removing refrigerant from the solution as it passes to the absorber and for replacing the refrigerant in the solution as it is conveyed away from the absorber to thereby increase the ability of the solution to absorb refrigerant in the absorber.

55 5. In absorption refrigerating apparatus the combination with an evaporator and an absorber of conduit means for conveying an absorption solution between them, means for removing refrigerant from the solution as it passes from the evaporator to the absorber, and means for replacing the refrigerant in the solution as it passes from the absorber to the evaporator, said last mentioned means including a pipe of small diameter adapted to function as a gas lift pump and cause circulation of the solution.

70 6. In absorption refrigerating apparatus, the combination with an evaporator and an absorber of conduit means for conveying an absorption solution between them, means including a gas lift pump for causing circulation of the solution thru said conduit means for removing refrigerant from

the solution as it passes from the evaporator to the absorber and means for replacing the refrigerant in the solution as it passes from the absorber to the evaporator.

7. The method of producing refrigeration which includes the steps of causing a refrigerant to evaporate from a solution thereof into an inert gas in an evaporator, conveying the gas laden with refrigerant vapor to an absorber, also conveying the solution from the evaporator to the absorber and changing the concentration of the solution as it passes from the evaporator to the absorber to enable it to absorb the refrigerant vapor from the inert gas at the same pressure but a higher temperature than that prevailing in the evaporator.

8. The method of producing refrigeration which includes the steps of circulating a solution of refrigerant thru an evaporator and an absorber, removing refrigerant from the solution as it passes from the evaporator to the absorber and replacing the refrigerant in the solution as it passes from the absorber to the evaporator.

9. The method of producing continuous refrigeration by causing a solution of refrigerant to pass thru a cycle, the steps of which consist of evaporating a refrigerant out of a solution to produce a cooling effect, heating the solution to weaken it further by expelling more refrigerant therefrom, causing the refrigerant first evaporated to be absorbed in the weakened solution and then causing the refrigerant expelled during the second mentioned step to be absorbed in the solution.

10. In a refrigerating system, an evaporator, an absorber, means for circulating a refrigerant gas between them, means for circulating a refrigerant liquor between the evaporator and the absorber and means for diverting a portion of the refrigerant contingent of said liquor from circulation with the liquor through said absorber.

11. In a refrigerating system, an evaporator, an absorber, means for establishing a refrigerant gas circuit between them, means for circulating a refrigerant liquor between the evaporator and the absorber, a separator in said liquor circuiting means operable to separate from the liquor at least a part of the refrigerant contingent thereof, means for conveying the weakened liquor to the absorber and means for returning the separated refrigerant contingent to the evaporator.

12. In a refrigerating system, an evaporator, an absorber, means for establishing a refrigerant gas circuit between the evaporator and the absorber, a separator in one of said conduits and operable to separate from the liquor at least a part of the refrigerant contingent thereof, a second absorber in the other of said conduits and means for conveying the refrigerant separated in said separator directly to said second absorber and thereby causing the separated refrigerant to by-pass the first mentioned absorber.

13. In a refrigerating system, an evaporator, an absorber, conduits for establishing a refrigerant liquor circuit between the same and means for by-passing at least a portion of the refrigerant contingent of the liquor from one conduit to another around said absorber.

14. In a refrigerant system, two vessels located at points relatively spaced from each other, means for circulating refrigerant liquor between said vessels and means for by-passing at least a portion of the refrigerant contingent of the liquor around one of said vessels.

15. In a refrigerating system, an evaporator,

85

90

95

100

105

130

- an absorber, means for establishing a refrigerant gas circuit between the same, conduits for circulating a refrigerant liquor between the evaporator and the absorber, a generator operable for vaporizing or gasifying at least a portion of the refrigerant contingent of the liquor while it is passing through one of said conduits, a second absorber associated with the other of said conduits, means for dividing said vaporized or gasified refrigerant portion, means for conducting one portion thereof into said second absorber for absorption by the refrigerant liquor passing therethrough and means for conducting the other portion into the channel of said refrigerant gas circuit for effecting a circulation thereof. 80
16. In a refrigerating system, two vessels located at points spaced from each other, conduits for circulating refrigerant liquor between said vessels and means for by-passing a portion of the refrigerant contingent of the liquor around one of said vessels, said means including a generator located in one of said conduits and an absorber in another of said conduits. 85
17. In a refrigerating system, two vessels located at points spaced from each other, conduits for circulating refrigerant liquor between said vessels and means for by-passing a portion of the refrigerant contingent of the liquor around one of said vessels, said means including a gas lift pump located in one of said conduits and an absorber in another of said conduits. 90
18. In a refrigerating system, an evaporator, an absorber, conduits for circulating a refrigerant liquor between the same, a generator operable to vaporize a portion of the refrigerant contingent of the liquor as it passes from the evaporator to the absorber, a second absorber associated with a conduit which conveys the liquor from the first mentioned absorber to the evaporator and operable to cause the portion of the refrigerant vaporized by the generator to be returned to the 95
19. In a refrigerating system, an evaporator, an absorber, conduits for circulating a refrigerant liquor between the same, a generator operable to vaporize a portion of the refrigerant contingent of the liquor as it passes from the evaporator to the absorber and also operable to cause circulation of the refrigerant liquor due to the vaporization of refrigerant therein, a second absorber associated with a conduit which conveys the liquor from the first mentioned absorber to the evaporator and operable to cause the portion of the refrigerant vaporized by said generator to be returned to the liquor in the conduit with which it is associated, whereby the portion of the refrigerant vaporized in said generator is by-passed around said absorber. 100
20. In a refrigerating system, an evaporator, an absorber, conduits for circulating a liquid between the same and a generator located in one of said conduits for expelling a vapor from said liquid. 105
21. In a refrigerating system, an evaporator, an absorber, conduits for circulating a liquid between the same and a generator located in one of said conduits for expelling a vapor from said liquid, said generator being so designed as to cause circulation of said liquid due to the expulsion of said vapor. 110
22. Refrigerating apparatus comprising a boiler, an absorber, an evaporator, a second absorber, and means to cause liquid to be thermosiphonically circulated from the boiler to the second absorber, from the second absorber to the first named absorber, from the first named absorber to the evaporator, and from the evaporator back to the boiler. 115
